UNITED STATES PATENT OFFICE.

CHARLES J. HARTLEY, OF DECATUR, ILLINOIS, ASSIGNOR OF TWO-THIRDS
TO JOHN K. WARREN AND BRADFORD K. DURFEE, BOTH OF SAME PLACE.

CONVEYER ATTACHMENT FOR THRASHING-MACHINES.

SPECIFICATION forming part of Letters Patent No. 434,338, dated August 12, 1890.

Application filed January 19, 1888. Renewed March 11, 1889. Serial No. 302,939. (No model.)

To all whom it may concern:

Be it known that I, CHARLES J. HARTLEY, of the city of Decatur, county of Macon, and State of Illinois, have invented certain new and useful Improvements in Attachments for Thrashing-Machines, of which the following is a specification.

It is the object of my invention to provide a thrashing-machine with elevating and conveying mechanism that may be compactly disposed in a manner to preserve equilibrium when the machine is on the road, and that will enable the grain to be discharged in various directions.

In the drawings accompanying and forming a part of this specification, Figure 1 is a side view of the elevator and an end view of the conveyer, showing both in working condition. Fig. 2 is a diminished side view of the elevator and conveyer, the actuating mechanism shown in Fig. 1 being omitted. Fig. 3 is a side view of the elevator in position for transportation, its operative position being shown by dotted lines. Figs. 4, 5, 9, 10, 11, 12, and 13 represent details of construction to be hereinafter specified. Fig. 6 shows the hopper of the conveyer with the casing broken to expose the interior thereof. Fig. 7 is a transverse vertical section of the hopper. Fig. 8 is a plan of the conveyer and the mechanism most nearly related thereto.

The elevator 1 has buckets, of the customary or any suitable construction, and also has spout 2. Conveyer 7 has hopper 6. Horizontal bar 8 connects with the conveyer under the center of the hopper and extends obliquely across the top of the thrasher to a pivotal connection near the center thereof. Concentric with the pivot of bar 8 is arc-formed bearing 9, clearly shown in Fig. 8. Bracket 95 is pivotally connected with shaft 26, as shown in Fig. 8, and bar 8 is firmly secured to the bracket. The bar 32 is also connected with the bracket, and it is slotted vertically at its outer end. A bolt with a clamp-jaw 33 and a nut with an adjusting-handle 34 provide means for securing the conveyer to bar 32. (See Fig. 12, where the bar is shown in

longitudinal vertical section and the bolt and nut in side elevation.)

The chain 10 is used to impart motion to the conveyer. The conveyer is braced under the hopper by approximately horizontal bar 11, extending from a lug on frame 21, and oblique rod 12, extending from the elevator. Secured to the elevator in a manner permitting pivotal motion is stud 13, and normally extending over said stud and over the conjoining lower end of rod 12 is sleeve 14. (See Fig. 5, where the sleeve is represented in section.) Frame 15 embraces the elevator and is provided with upper bearings for shaft 17 and lower bearings for the trunnions of frame 21. Shaft 4 in frame 21 carries bevel-pinion 75 and sprocket-wheel 30. Shaft 19 carries bevel-pinion 20 and sprocket-wheel 29. Shaft 3 carries bevel-pinion 27 and sprocket-wheels 28 and 74. (See Fig. 9, where the frame with its mechanism is illustrated in detail.) Tubular shaft 26 traverses the top of the thrashing-machine and is adapted to receive at either end an end of shaft 3. Bearings 31 hold shaft 26 and are themselves held by diverging braces 22 23, suitably secured to the sides of the machine.

In hopper 6 is cone 36, mounted on tubular shaft 45. On the shaft under the cone is sprocket-wheel 38. The chain 39 on wheel 38 has vertical scrapers 40. Plate 41 under the conveyer furnishes an extended bearing for shaft 45. Plate 43, having stepped surfaces, as shown in Fig. 7, is secured to plate 41 by bolts 44, and band 42 is held in the intervening space in a manner permitting free rotation. Slotted lugs 51 extend from opposite sides of band 42 and register with lugs on frame 25. Bolt 48 extends through frame 25 and provides a journal for sprocket-wheel 47, which is provided with an upwardly-projecting rim 46, that forms a square socket 90 that receives the square block 85 on the lower end of shaft 45. The shaft 45 is closed at its lower end, has lateral openings, as shown, and is provided with removable plug 37 in its upper end.

The elevator is sustained by shaft 17, which

is adjustably secured to shaft 26 by clips 35. (See Fig. 13, where the shafts are shown in section and a clip in side elevation.)

The conveyer has longitudinal partition 56, and the hopper has partial covering 55. (See Fig. 8.) While the device is in operation the outer end of the conveyer is sustained from the upper end of the elevator through pivoted arm 54, rod 53, and bail 52, and the frame 25 is held in connection with band 42 by bolts 50, which have oblong heads. When it is desired to arrange the parts preparatory to going on the road, the conveyer is swung into the position shown in solid lines in Fig. 8, the rod is detached from the bail, and the conveyer is clamped to bar 32. Bolts 50 are turned to pass through their slots, the sleeve 14 is raised clear of the junction of the stud with the rod, and the rod is disconnected from the stud and lowered until the bolts are clear of the band. The conveyer is then swung to the position shown by broken lines in Fig. 8, the rod 12 is reconnected with the stud, the clips 35 are loosened, and the elevator is swung to the position shown by solid lines in Fig. 3. It only remains to secure the elevator and the conveyer in their new positions, which may be done in any desirable manner, and the machine is in complete equipoise and ready for the road. In effecting this adjustment there has been no disarrangement of drive-chains, and consequently there will be no necessity for rearrangement when the machine is again put in operation.

The shaft 19 is the center from which all motion is distributed. The chain 72 (shown in Fig. 1) connects wheel 28 (see Fig. 11) with a wheel of the thrashing-machine. The direction of the rotation of wheel 28 is immaterial, as if in one direction connection may be made from wheel 74 with a drive-wheel on one side of the elevator, and if in the contrary direction connection may be made from the reversely-rotating wheel 29 with a drive-wheel on the opposite side of the elevator, the chain 73 acting as the power-transmitter in either case. The rotation of wheel 30, through which the conveyer-chain is driven, may be reversed to suit circumstances by placing pinion 75 in mesh with the upper surfaces of pinions 20 and 27, instead of with the lower surfaces, as shown in Fig. 9. This indifference to the direction of the rotation of the main shaft enables connection to be made with the most accessible shaft of the thrasher.

When the conveyer is in operation it may be turned in any direction.

The partial covering of the hopper obviates the necessity of carrying any considerable quantity of grain around the sprocket-wheel, and the cone acts as an agitator of the grain and a protector of the sprocket-wheel.

The shaft 45 is to be oiled internally through the opening, usually closed by removable plug 37.

The device as a whole is well adapted to

be used with an automatic scale and register, which may be easily secured to the spout of the elevator.

I claim as new and desire to secure by Letters Patent—

1. An attachment for thrashing-machines, comprising the elevator 1, pivotally connected with the side of the machine, the bar 8, pivotally connected with the top of the machine, the conveyer 7, pivotally connected with the swinging end of bar 8, and the detachable connection 52 53, extending from the top of the elevator to the swinging end of the conveyer, as and for the purpose set forth. 80

2. An attachment for thrashing-machines, comprising the elevator 1, the conveyer 7, having longitudinal partition 56 and hopper 6, the vertical shaft 45, carrying sprocket-wheel 38 and cone 36, and the chain 39, carrying scrapers 40, as and for the purpose set forth. 85

3. An attachment for thrashing-machines, comprising the elevator, the conveyer 7, having longitudinal partition 56, the hopper 6, partly covered at 55, the tubular shaft 45, 90 closed at its lower end and perforated in its bearings, the cone 36, the sprocket-wheel 38, and the chain 39, carrying scrapers 40, as and for the purpose set forth.

4. An attachment for thrashing-machines, 95 comprising the elevator, the conveyer 7, having pivotal ring 42, the frame 25, detachably secured to the ring, the block 85 on the shaft of the conveyer, and the sprocket-wheel 47, mounted in frame 25 and provided with 100 socket 46, adapted to the block, as and for the purpose set forth.

5. An attachment for thrashing-machines, comprising the elevator, the conveyer 7, pivoted on ring 42, the bar 8, connected with the 105 ring and pivotally secured to the top of the machine, and brace-bar 32, adapted to connect with the conveyer, as and for the purpose set forth.

6. An attachment for thrashing-machines, 110 comprising the elevator, the arc-formed way 9, the plate 95, adapted to pivot concentric therewith, the bar 8, extending from plate 95 to ring 42, the conveyer 7, pivoting on the ring, and the bar 32, carrying clamp-bolt 33, 115 as and for the purpose set forth.

7. An attachment for thrashing-machines, comprising the conveyer, the tubular shaft 26, traversing the machine, the shafts 3 and 19 in line therewith, the shaft 17, adjustably secured to shaft 26 by clips 35, the frame 15, secured to shaft 17 and providing bearings for shafts 3 and 19, and the elevator 1, supported in frame 15, as and for the purpose set forth. 125

8. An attachment for thrashing-machines, comprising the elevator, the conveyer, the frame 21, providing pivotal bearings, the elevator-shafts 3 and 19, having opposing bevel-pinions 20 and 27, power-receiving wheel 28 130 and power-imparting wheels 29 74, and vertical shaft 4, provided with bevel-pinion 75

and sprocket-wheel 30, adapted to impart power to the conveyer, as and for the purpose set forth.

9. An attachment for thrashing-machines, consisting in the combination of the elevator 1, the conveyer 7, the ring 42, on which the conveyer pivots, the frame 25, detachably secured to the ring, the brace-rod 12, the stud

13, and the sleeve 14, normally embracing the stud and the lower end of the rod, as and for the purpose set forth.
